DESIGN FOR A CHILD'S ROCKING DEVICE

Ben C. Timmerman, Hibbing, Minn.

Application February 3, 1945, Serial No. 117,741

Term of patent 14 years

(Cl. D34—15)

To all whom it may concern:

Be it known that I, Ben C. Timmerman, a citizen of the United States and residing in the city of Hibbing, county of St. Louis, State of Minnesota, have invented a new, original, and ornamental Design for Child's Rocking Device, of which the following is a specification, reference being made to the accompanying drawing, forming a part thereof, wherein:

Fig. 1 is a top plan view of a child's rocking device showing my new design;

Fig. 2 is a side elevational view thereof;
Fig. 3 is a rear elevational view of the same;
and

Fig. 4 is a front elevational view.

I claim:

The ornamental design for a child's rocking device, as shown.

BEN C. TIMMERMAN.
